UNITED STATES PATENT OFFICE.

WILLIAM ZAISER, OF ROCKVILLE CENTER, NEW YORK.

DESIGN FOR A GRAND PIANO.

Application filed July 25, 1928. Serial No. 27,574. Term of patent 14 years.

To all whom it may concern:

Be it known that I, WILLIAM ZAISER, a citizen of the United States, and a resident of Rockville Center, Nassau County, New York, have invented a new, original, and ornamental Design for a Grand Piano, of which the following is a specification, reference being had to the accompanying drawing, forming part thereof.

The drawing is a perspective view of a grand piano illustrating my new design.

I claim:

The ornamental design for a grand piano substantially as shown.

In testimony whereof I have hereunto signed this specification.

WILLIAM ZAISER.
